PUMPING APPARATUS

Filed June 21, 1928

UNITED STATES PATENT OFFICE

IRWIN B. WINSOR, OF TULSA, OKLAHOMA

PUMPING APPARATUS

Application filed June 21, 1928. Serial No. 287,110.

My invention relates to apparatus for conducting a flow of fluid from wells and constitutes an improvement over my previous Patent No. 1,637,629.

5 The principal object of my present invention is to provide for the operation of a pump at the bottom of a well by a power generator, preferably an air motor, positioned in the well casing, above and in close proximity to the pump, thereby eliminating the usual string of sucker rods connecting the pump with actuator means at the top of a well.

A further object of the invention is to 15 divide and seal the well into upper and lower portions by means of a packer interposed between the motor and pump and having a sealed relation with the casing, so that the casing serves as a conduit for conducting the 20 fluid from a well.

A further object of the invention is to provide valve outlet passages in the packer, whereby gas pressure accumulating in the lower well portion may be admitted to the 25 upper well portion and assist in lifting the fluid upwardly through the well.

In accomplishing these and other objects of the invention, I have provided improved details of structure, the preferred forms of 30 which are illustrated in the accompanying drawings, wherein:

Fig. 1 is a central sectional view of the lower portion of an oil well showing the apparatus applied therein.

35 Fig. 2 is an enlarged sectional view of the lower part of the apparatus.

Fig. 3 is an enlarged fragmentary sectional view of the upper part of the apparatus showing the connection of the plunger 40 rod with the piston rod of the motor.

Fig. 4 is a section on the line 4-4 of Fig. 2.

Referring in detail to the drawings:

1 designates an oil well lined with casing 45 2 having a casing shoe 3 at its lower end which rests on the cap rock 4 and thus serves to support the casing. The cap rock 4 overlies the oil sand 5 and an oil pocket 6 formed in the sand contains oil 7 which flows through the sand into the pocket.

50 My pumping apparatus in its order of as-

sembly from the bottom of a well includes a strainer 8 resting on the bottom of the well pocket, a pump 9 supported on the strainer and fitted at its upper end with a coupling collar 10. A well packer 11 is mounted in the coupling and fitted at its upper end with a liner 12 supporting an air motor 13, the motor being connected with a compressor or other source of compressed air by a conduit 14 extending upwardly through the well casing.

The strainer 8 by its engagement with the bottom of the pocket 6 serves to support the assembled pumping apparatus, and ports 15 adjacent its upper end serve to strain the fluid entering therein for displacement from the well by the pump 9. A collar 16 on the strainer includes a web 17 carrying a standing valve 18 whereby fluid entering the pump from the strainer is checked from return flow to the well pocket.

The pump 9 comprises a barrel 19 mounted in the collar 16 and fitted with a piston 20, the piston being provided with a central opening 21 fitted with a ball check valve 22 and threaded at its upper end for connection with a tubular plunger rod 23.

Attached to the upper end of the pump barrel 19 is the coupling collar 10 engaged by a nipple 25 provided with an enlarged body portion 26 and a reduced threaded upper end 27 engaged in the internally threaded collar 28 at the bottom of the packer 11.

A plurality of vertically extending and equally spaced valve chambers 29 are provided in the enlarged body portion 26 of the nipple 25 and fitted with ball check valves 30, the chambers having ports 31 extending inwardly from the ports below the tops thereof, and reduced ports 31' in the bottoms thereof for admitting gas under pressure from the lower part of the well through the chambers and ports into the pump barrel chamber 32 when pressure in the well exceeds that in the pump barrel and to stop flow of gas from the pump barrel back to the well.

The packer 11 comprises the usual cylindrical body 33 having an annular groove 34 carrying a packing ring 35 of rubber or other

resilient packing material which sealingly engages the walls of the well casing and serves to divide the well into upper and lower sealed portions.

Extending vertically and centrally through the packer is an opening 36 for receiving the plunger rod 23 for free reciprocating movement therein, and mounted in an enlarged threaded portion at the upper end of the packer is a packing gland 37 sealingly engaging the plunger in its working relation with the packer for preventing leakage of fluid from the upper well portion into the pump chamber 32.

A plurality of equally spaced ducts 38 are provided in the body 33 of the packer and extend upwardly from the bottom of the body for communication with ports 39 in the packing gland 37, ball check valves 38' being provided at the lower ends of the ducts 20 for controlling the flow of the gas pressure into the upper well portion.

Threadedly engaged in the ports 39 of the packing gland 37 are nipples 40 fitted with caps 41 and provided with side outlet openings 42 through which the gas pressure is admitted to the upper well portion, the closed ends serving to prevent the precipitating sand or sediment from the fluid from entering and clogging the ducts 38 and ports 39.

Mounted in the upper and internally threaded opening of the packer body 33 is a reducer collar 43 threadedly engaged by the liner 12 which supports the air motor 13, the liner being provided with ports 44 to permit the passage of gas pressure and fluid therefrom into the surrounding upper well portion.

In order to effect reciprocation of the hollow pump plunger 23, I prefer to employ an air motor of the reciprocating type and to connect the end of the motor piston rod 45 with the upper end of the plunger rod by means of a threaded coupling 46 (Fig. 3).

In order to permit the fluid to pass from the hollow plunger into the liner 12 I provide apertures 47 in the walls of the plunger, so positioned as to remain open to the liner 12 throughout the travel of the plunger.

In practicing the method with the apparatus disclosed, air pressure is admitted to the air motor 13 through the conduit 14 for setting the motor in operation.

Reciprocating movement imparted to the hollow plunger 23 of the pump 9 causes the fluid to be drawn into the pump barrel 19 through the standing or check valve 18 during the upstroke of the pump piston 20. On the succeeding down stroke of the piston 20, the fluid trapped in the barrel 19 opens the check valve 22 in the piston and passes upward through the plunger and through the plunger openings 47 into the liner 12. The fluid passes from the liner through the ports 44 into the upper well portion defined by the

casing, the packer 11 in its sealed relation with the casing serving as a bottom for the upper well portion to support the column of fluid as it is built up therein and finally fills the casing and flows off from the top of the well through suitable flow lines (not shown). 70

Gas pressure accumulating in the lower portion of the well is free to escape into the upper well portion above the packer through the valved ports when its natural pressure is sufficient to overcome the hydrostatic pressure of the column of fluid contained in the upper well portion, or when it is sufficiently compressed in the pump barrel 19 during the upstroke of the piston 20 to overcome the resisting fluid pressure. 80

What I claim and desire to secure by Letters Patent is:

1. In combination with well casing, a packer in the casing, a liner rising from the packer, and having ports opening to the casing, a motor on the liner, a pump barrel located beneath the packer, a valved plunger in said barrel, and a hollow rod connecting the motor with the plunger and having ports opening to the liner. 90

2. In combination with well casing, a packer in said casing having valved ducts providing communication between the upper and lower portions of the casing, a pump barrel below and in sealed relation with the packer having valved ports providing communication between the barrel and the well, a liner above the packer having ports opening to the casing, a plunger in the pump barrel, a hollow pump rod extending through the packer, connected with the pump plunger and having ports opening to the liner, a valve in the plunger controlling flow from the pump barrel to the hollow rod, and means for reciprocating said rod. 100

In testimony whereof I affix my signature.

IRWIN B. WINSOR.
